UNITED STATES PATENT OFFICE.

CHARLES J. PILLIOD, OF TOLEDO, OHIO.

MECHANICAL STOKER.

1,198,148.

Specification of Letters Patent. Patented Sept. 12, 1916.

Application filed September 8, 1914. Serial No. 860,694.

To all whom it may concern:

Be it known that I, CHARLES J. PILLIOD, a citizen of the United States of America, residing at Toledo, in the county of Lucas and State of Ohio, have invented certain new and useful Improvements in Mechanical Stokers, of which the following is a specification, reference being had therein to the accompanying drawings.

10 The invention relates to mechanical stokers, and has particular reference to a construction in which the fuel is fed into the furnace centrally thereof and is distributed by a blast over the fuel bed and to the sides 15 of the furnace chamber.

It is one of the objects of the invention to obtain a uniform distribution of the fuel so as to produce the highest efficiency in heat generation, and a further object is to 20 obtain a construction which will operate equally well with a slow or a fast fire.

With these objects in view, the invention comprises the construction as hereinafter set forth.

25 In the drawings: Figure 1 is a plan view; Fig. 1^a is a longitudinal section through the fuel trough and fuel feed motor; Fig. 2 is a cross section thereof; Fig. 3 is a section through the valve-operating motor; Fig. 4 is a cross section on line x-x Fig. 3; and Fig. 5 is a side elevation of the cam wheels.

A is the combustion chamber of a furnace, such as that for a locomotive boiler.

B is a trough-shaped casing arranged centrally and extending longitudinally of the furnace chamber, below the grate level thereof.

C is a hopper arranged outside of the furnace and communicating with the casing B.

40 D is a reciprocating fuel-pusher for propelling the fuel from the hopper C into the furnace chamber, and E is a piston motor for operating the fuel pusher.

Distributed along the casing B near the 45 upper edge thereof are ports or twyrs F, which are connected with channels G formed in the casing and extending out from the furnace chamber. These channels are connected by pipes G' with a source of 50 blast, preferably steam from the boiler, which, however, is controlled by valves automatically operated by a timed mechanism. The piston motor E which operates the fuel pusher is also controlled by automatically 55 operated valves, and I preferably employ a common mechanism for operating all of

these valves, which permits of varying the timing, as hereinafter set forth.

As shown, H is a casing, within which is arranged a motor I, preferably a three-cylinder, single-acting piston motor which will be self-starting.

J is a step-down drive train actuated by the motor I, shown in the form of a worm gearing.

65 J' is a crank actuated by the train J, and J² is a pitman rod connecting said crank to a rock-arm K for actuating a rocker valve K'. This valve controls the admission of steam to the piston motor E which operates 70 the reciprocating pusher, and consequently the speed of operation of said pusher is governed by the speed of operation of the motor I. The steam pipes leading to the piston motor E from the casing H and controlled 75 by said valve K' are designated by the numeral K². Operated by this same motor I is a transmission and governing mechanism which controls the valves for admitting the blast to the twyrs F. This mechanism as 80 specifically shown comprises a shaft L which is driven from the crank shaft of the motor I through the medium of a sprocket and chain drive connection L'.

M M' M², etc., are a series of worm shafts 85 extending transversely to the shaft L and driven from the latter through the medium of beveled gears L².

N is a shaft parallel to the shaft L and N' is a tubular shaft telescopically engaging 90 the same.

O is a worm wheel keyed upon the tubular shaft N' and meshing with the worm M, so as to be driven thereby and to transmit rotary movement to said shaft.

95 O' is a worm wheel intermeshing with the worm M' and mounted upon a sleeve O² rotatively engaging the shaft N'.

P P' and P² are disk-shaped cams arranged adjacent to each other, the cam P 100 being secured to the sleeve O², the cam P' to the tubular shaft N', and the cam P² to a sleeve P³ which has a spiral slot P⁴ engaging a pin P⁵ extending transversely through the shaft N, and also passing 105 through a longitudinal slot P⁶ in the tubular shaft N'. The construction is such that a relative longitudinal movement of the shaft N and tubular shaft N' will cause the pin P⁵ to travel in the longitudinal and spiral slots P⁶ and P⁴, and a roller P⁷ on the pin in the latter slot will effect a rotati

adjustment of the sleeve P^3 thereby rotatively adjusting the cam P^2 .

The relative longitudinal movement of the shafts N and N' is effected by a centrifugal governor Q which is sleeved upon said shafts, and is driven through the medium of a sprocket Q' , chain Q^2 and sprocket Q^3 on the engine crank shaft. Thus any variation in the speed of said crank shaft will effect said governor and will cause a bell-crank arm Q^4 engaging a collar N^4 on the shaft N to move said shaft longitudinally.

The cams P , P' and P^2 together constitute a compound cam which actuates a rod R connected to a rocker arm R' upon the stem of a rocker valve R^2 for controlling the blast to one of the twyrs F . The rod R has at its lower end a roller R^3 which engages the periphery of the compound cam and it moves inward and outward by the fashioned contour thereof. The cam P is driven through the worm gearing O' and M' at a relatively slow rate, and once in each revolution registers a depressed portion in its periphery with the roller R^3 . The cams P' and P^2 are driven at a higher rate of speed and operate respectively as timing cams respectively for dropping and lifting the roller R^3 when in registration with the depression in the cam P , but in all other positions of said cam P the cams P' and P^2 are ineffective. Furthermore, the timing of these cams to the interval between the dropping of the roller and the raising of the same is dependent upon the relative adjustment of said cams, which in turn is dependent upon the governor Q and the speed at which it is rotated. Thus a variation in speed will cause the governor to 40 either move the shaft N outward in the tubular shaft N' or permit a spring N^6 to move said shaft in the opposite direction. Each of these movements will through the medium of the pin P^5 engaging the spiral slot P^4 in the sleeve P^3 cause a rotative adjustment of said sleeve, which varies the relation of the cams P' and P^2 . The purpose of the whole construction is to adjust the cam whenever there is a change in speed 45 of the motor shaft, so that the interval in which the valve controlling the twyer is open remains substantially constant regardless of variations in speed of the motor. On the other hand, any variation in the speed of the motor will cause a variation in the operation of the fuel pusher actuated thereby, either increasing or decreasing the quantity of fuel fed into the trough B . The supply of steam (or equivalent fluid) to the 50 valve R^2 is through a pipe G^3 entering the top of the casing H , (see Fig. 4). The relation of the piston motor E to the casing H is well shown in Fig. 4.

It will be understood that there is a duplicate mechanism, comprising a compound

cam and connections for controlling each of the valves for the respective twyers, and all of these mechanisms operate simultaneously and correspondingly to produce the same timing in each valve.

With the construction as thus far described in operation, the fuel which is deposited in the hopper C will be periodically fed in measured quantities by the reciprocating pusher D actuated by the piston motor E , and will be forced into the trough B and upward therein so as to cover the twyers F . Whenever the valve R^2 is open the blast admitted to the twyers F will blow the fuel from the trough B and will distribute it over the bed of the ignited fuel in the furnace chamber, the distribution being the same throughout the length. The time interval during which the blast is in operation will remain constant, as before stated, which is desirable, as the best results are obtained by feeding the fuel over the bed at a constant rate; but the operation of the pusher will vary with the speed of the motor I , so that where said motor is accelerated the time interval between successive periods of operation of the pusher are increased, while the slowing of the motor I will decrease the length of interval between periods of operation. By means of this arrangement, the operator is enabled to increase or diminish the quantity of fuel fed into the furnace by varying the speed of the motor I , which is controlled by an adjustable throttle valve, but this alteration in the quantity of fuel fed does not interfere with the uniformity of the distribution of the fuel over the furnace bed when the twyers are in operation.

To produce the best results in the operation of the furnace it is required that the fuel distributed to different parts of the furnace chamber should be exactly proportionate, and this necessitates a plurality of the twyers F distributed along the trough B , and also an adjustment of the strength of blast passing through each twyer to effect the desired operation upon the fuel. I have therefore provided a separate valve R^2 for each of the twyers F , and have further provided a separate throttle valve S operating in conjunction with the valve R^2 and permitting of varying the strength of blast of the different twyers. As shown the valve S is arranged above the corresponding valve R^2 , while the latter controls the opening into a chamber T which is connected by a suitable conduit with the corresponding twyer.

One of the difficulties with automatic stokers for locomotive boilers has been to distribute the fuel to the sides of the furnace chamber. With my improved construction in which the fuel is fed from the center of the furnace there is no difficulty in distribut-

ing it to the sides and consequently the improved results are obtained.

What I claim as my invention is:—

1. In a stoker, the combination with means for variably feeding the fuel into the furnace chamber, of means for distributing said fuel at a uniform rate over the furnace bed, the rate of distribution remaining substantially constant during variations in the rate of feeding. 70
2. In a stoker, the combination of means for feeding measured quantities of fuel into the furnace chamber at varying intervals, and means for distributing said measured quantities of fuel at a constant rate over the fuel bed, the rate of distribution remaining substantially constant during variations in the rate of feeding. 75
3. In a stoker, the combination with mechanical means for periodically feeding fuel into the furnace chamber, of pneumatic means for distributing the fuel over the furnace bed, timed mechanism controlling the sequential operation of said mechanical feeding and pneumatic distributing means, and means for varying the speed of operation of said mechanical feeder without changing the rate of distribution of said pneumatic means. 80
4. In a stoker, the combination with means for feeding a measured quantity of fuel into the furnace chamber centrally thereof, mechanical means for distributing the fuel to the center portion of the furnace bed, and pneumatic means for distributing said fuel over the furnace bed and to the extreme sides thereof. 90
5. In a stoker, the combination of mechanical means for feeding measured quantities of fuel into the furnace chamber, a motor for operating said feeding means, means for varying the speed of said motor, pneumatic means for distributing the fuel fed into the furnace, a valve controlling said pneumatic means periodically operated by said motor, and means for maintaining the period of opening of said valve constant independent of variations in the speed of the motor. 100
6. In a stoker, the combination of mechanical means for feeding measured quantities of fuel into the furnace, pneumatic means for distributing the fuel in the furnace chamber, a continuously operating motor for periodically operating said mechanical feeding means and also periodically opening and closing said pneumatic distributing means, means for varying the speed of said motor, and means for maintaining the period of opening of said pneumatic means constant during variations in speed of said motor. 115
7. In a stoker, the combination with means for feeding measured quantities of fuel into the furnace chamber, of a blast twyer for distributing the fuel fed into said chamber, a valve for opening and closing said blast twyer, a continuously operating motor for periodically operating said fuel feeding means and for also opening and closing said valve after each periodic feeding, means for varying the speed of said motor to vary the intervals between successive feeding operations, and means for automatically maintaining the interval of opening of said valve substantially constant independent of variations in speed of the motor. 120
8. In a stoker, the combination with the furnace chamber, of a fuel receiving trough extending longitudinally of said chamber and provided with a blast twyer, means for periodically feeding fuel into said trough, and means for automatically opening said blast twyer to distribute the fuel received by said trough. 125
9. In a stoker, the combination with the furnace chamber, of a fuel receiving trough extending longitudinally thereof, means for periodically feeding measured quantities of fuel into said trough, and co-acting means for pneumatically distributing the fuel from said trough over the furnace bed. 130
10. In a stoker, the combination with a furnace chamber, of a fuel receiving trough having a plurality of blast twyers distributed along the length thereof, means for periodically feeding measured quantities of fuel into said trough, co-acting means for periodically opening and closing said twyers to pneumatically distribute the fuel over the furnace bed, and means for independently controlling said twyers to vary the distribution effected thereby. 135
11. In a stoker, the combination with a furnace chamber, of a trough extending longitudinally thereof, a fuel hopper, a reciprocatory pusher for feeding measured quantities of fuel from said hopper into said trough, a pneumatic motor for operating said pusher, a blast twyer for distributing the fuel from said hopper over the furnace bed, a valve controlling said twyer, a continuously operating motor, connecting mechanism for operating from said motor the valve controlling said feeder motor and twyer, means for varying the speed of said continuously operating motor, and a governor for maintaining the period of opening of said blast twyer substantially constant independent of variations in the speed of said motor. 140
12. In a stoker, the combination with means for feeding fuel into the furnace chamber, of means for distributing the fuel comprising a plurality of fluid conducting pipes discharging within the furnace chamber, valves respectively controlling the flow through said pipes, a common means for periodically opening and closing said valves, 145

and mechanism respectively associated with the valves for maintaining their period of opening constant during variations in speed of the actuating means.

- 5 13. In a stoker, the combination with means for feeding fuel into a furnace chamber, of a motor for actuating said means, pneumatic means for distributing the fuel within the furnace, a second motor periodically opening and closing said pneumatic distributing means, means establishing a substantially constant speed ratio between the two motors, and means for maintaining the period of opening of the pneumatic means substantially constant during variations in speed of the motors.
- 10 14. In a stoker, the combination with the furnace chamber, of a fuel-receiving trough therein, means for periodically forcing fuel into one end of the trough, and means acting periodically directly upon the fuel in the

top portion of the trough to displace it laterally to each side of the trough.

- 15 15. In a stoker, the combination with means for feeding measured quantities of fuel into the furnace, of a piston motor actuating said means, pneumatic means for distributing said fuel, a valve controlling the application of fluid to the piston motor, a valve controlling said pneumatic means, and a second motor periodically opening and closing the valve controlling the piston motor at a rate proportionate to the speed of said second motor and periodically opening and closing the other valve at a substantially unvarying rate.

In testimony whereof I affix my signature in presence of two witnesses,

CHARLES J. PHILLIPS,
